Application July 11, 1942, Serial No. 450,595

13 Claims. (Cl. 172—239)

1

The present invention relates to means for reproducing motion, and more particularly to novel and improved means for reproducing angular motion at a remote point for indicating and/or control purposes.

One of the objects of the invention is to provide novel means for reproducing motion, constituting an improvement over the means disclosed in the patent to W. A. Reichel, No. 2,269,602, dated January 13, 1942, said patent being assigned to the same assignee as the present invention.

Another object is to provide a novel telemetric system wherein a transmitter of the self-synchronous motor type, generally known as a "Selsyn" motor, may be employed, using alternating current for energization thereof, and connected to a remote receiver of a direct current type instead of to a self-synchronous motor receiver.

A further object of the invention is to provide novel and improved means for reproducing motion, employing a transmitter of the type disclosed in the aforesaid patent to Reichel, No. 2,269,602, which employs a periodically varying or alternating current for energization thereof, and electrically connected through rectifiers to a direct current type of indicator having a permanent magnet rotor, for example.

Still another object is to provide novel means for reproducing angular motion at a remote point, comprising a transmitter energized by an alternating current and electrically connected through rectifiers to a direct current type of indicator at the remote point, said indicator being additionally energized by direct current from a local D. C. source.

The foregoing and other objects and advantages of the invention will appear more fully hereinafter from a consideration of the detailed description which follows, taken together with the accompanying drawings wherein three embodiments of the invention are illustrated by way of example. It is to be expressly understood, however, that the drawings are for purposes of illustration only and are not to be construed as defining the limits of the invention, reference being had for this purpose to the appended claims.

In the drawings:

Fig. 1 is a more or less diagrammatic illustration of one embodiment of the invention wherein an alternating current transmitter of the self-synchronous motor type is electrically

2

connected to a remote receiver of a direct current type;

Fig. 2 is a diagrammatic illustration of another embodiment wherein an alternating current transmitter of a different type is connected to a direct current type receiver; and

Fig. 3 is another diagrammatic illustration of a third embodiment wherein the transmitter is like that of Fig. 2, but the receiver is somewhat different although still of the direct current type.

The invention consists substantially in the construction, combination, location and relative arrangement of parts and circuits for obtaining the results desired in accordance with the foregoing objects, as will be more fully hereinafter set forth in the specification, as shown in the drawings by way of example, and as finally pointed out in the claims.

Referring now to the drawings and more particularly to Fig. 1, the novel apparatus embodying the invention, comprises, in the form shown, an alternating current type of transmitter 4 which, in this embodiment, is shown as a self-synchronous motor, and a direct current type of receiver 5 electrically connected to said transmitter in a manner which will be explained more fully hereinafter.

The transmitter 4 comprises a rotor having a single phase winding 6 and a stator having three windings 7, 8 and 9, one end of each being connected together at 10 in Y relation to form a three-phase type of winding arrangement constituting the output of said transmitter.

The remote receiver 5 comprises a stator having three direct current windings 11, 12 and 13 spaced 120 degrees apart around a rotor 14 which is in the form of a circular magnet having a north pole and a south pole indicated at N and S, said rotor being drivably connected in any suitable manner (not shown) to a control device or, as shown, to a pointer 15 of an indicator 16.

The rotor winding 6 of the transmitter 4 is arranged for energization by an alternating current through leads 17 and 18 connected to the supply leads 19 and 20. The supply lead 19 is also connected to the common junction 10 of the stator windings 7, 8 and 9 the other ends of which are respectively connected to one input terminal of full-wave rectifiers 21, 22 and 23 by means of leads 24, 25 and 26, respectively, the other input terminal of each of said rectifiers being connected to the A. C. supply lead 20. Thus, a voltage is produced in each of the output windings 7, 8 and 9 which is the algebraic sum of the voltage applied directly from the supply lines 19, 20 and

the voltage induced in each of said windings by the rotor winding 6, the latter voltage varying in each of said windings 7, 8 and 9 in accordance with the angular position of said rotor winding 6 with respect to the stator windings 7, 8 and 9.

The resultant A. C. voltage in each of the windings 7, 8 and 9 is then rectified by the full wave rectifiers 21, 22 and 23, respectively, and the rectified voltages are supplied to the D. C. stator windings 13, 12 and 11, respectively, of the receiver, whereby a resultant uni-directional field is produced, the direction of which corresponds to the angular position of rotor winding 6 of the self-synchronous transmitter motor 4. This resultant field reacts with the field of the magnet rotor 14 of the receiver, whereby said rotor is caused to assume an angular position with respect to the stator windings 12, 13 and 11 corresponding to the angular position of said rotor winding 6 with respect to the stator windings 7, 8 and 9 of the transmitter, as shown in Fig. 1, thereby actuating the pointer 15 of the indicator 16 to indicate said position on a scale.

The rotor winding 6 of the transmitter may be actuated either manually or by a measuring device, the indications of which are to be transmitted to the remote point at which the receiver 5 is located. For simplicity, the actuating device is represented diagrammatically by the arrow 28 shown connected to the rotor 6 by the dotted line.

Referring now to Fig. 2, there is shown another embodiment of the invention, wherein the transmitter is of the type disclosed in the aforesaid patent to Reichel No. 2,269,602, but connected to a D. C. type of indicator. The transmitter is shown at 29 and the remote receiver at 30.

The transmitter 29 comprises a stator having an annular core 31 of highly permeable magnetic material such as "Permalloy" or "Mu-metal," for example, on which is wound a single phase primary or exciting winding 32 over the entire circumference thereof, said exciting winding 32 being connected for energization by an alternating current from supply leads 19 and 20 by leads 33, 34 which are also connected to a frequency doubler of any suitable type shown diagrammatically at 35, for a purpose which will be explained hereinafter. By virtue of the alternating current flowing in the single phase exciting winding, the permeable core member 31 is periodically saturated at a frequency corresponding to the frequency of said alternating current.

Wound over said exciting winding 32 and in inductive relation therewith are three windings 36, 37 and 38 and are connected in three phase relation at the junction point 39 to form a Y-connected three phase type of winding.

Concentrically arranged within the stator core member 31 and in magnetic relation therewith is a rotor 40 in the form of a magnetic member of marked polarity as, for example, a rotatable permanent magnet having north and south poles as indicated at N and S, providing a uni-directional magnetic field which enters the core member 31 at the north end of said rotor, divides into two paths so that part of the flux flows to the left and part to the right, as viewed in Fig. 2. These fluxes then combine and emerge from the core at the south end of the rotor where they enter the latter. The rotor magnet 40, in the present instance, is shown in the form of a disc, the upper half of which constitutes the north pole and the lower half the south pole thereof.

In the event that it is desired to transmit the indications of a magnetic compass to the remote

point, the rotor 40 may be dispensed with, and the stator 31 placed under or above the compass in influencing relation with the compass magnet, whereby the latter then becomes the rotor of the transmitter.

Likewise, the transmitter 29 may be used as an earth inductor, in which event the rotor 40 may again be dispensed with and the stator placed in a horizontal position and arranged so as to be traversed by the earth's magnetic field, the latter then traversing the core member 31 in the same manner as the uni-directional field of the rotor 40, but in that case the field obviously remains stationary and the stator is then moved angularly in azimuth.

The receiver 30 in the embodiment shown in Fig. 2 is a direct current type somewhat like that shown in Fig. 1 and, as shown, comprises a stator having three pairs of windings, one pair being shown at 41, 42, the second pair at 43, 44 and the third pair at 45, 46, said pairs being arranged around a magnet rotor 47 and angularly spaced 120 degrees apart. The rotor 47 is drivably connected to actuate a pointer 48 over a scale of the indicator 49.

Upon energization of the exciting winding 32 of the transmitter 29 by the alternating current, voltages are generated in the three output windings 36, 37 and 38 due to the periodic reversal of the flux produced in the core 31 by said energizing current, because of the fact that during one half-cycle of said current the periodically reversing flux opposes the uni-directional flux of the magnet rotor 40 in one half of said core 31 and, at the same time, aids said uni-directional flux in the other half of said core, while during the other half-cycle of said exciting current said periodically reversing flux aids the uni-directional flux of the magnet rotor 40 in the one half of said core 31 and, at the same time, opposes said uni-directional flux in the other half of said core, as fully explained in the aforesaid patent to Reichel, No. 2,269,602. The voltages thus generated in the output windings 36, 37 and 38 by the flux variations in core 31 are even harmonics, mostly second harmonics, of the fundamental frequency of the exciting current. These second harmonic voltages are in phase and vary only in magnitude with the position of the magnet rotor 40 with respect to the three windings 36, 37 and 38 which are angularly spaced 120 degrees apart around said core 31 and, hence, with respect to the rotor 40.

Means are now provided for dividing the output voltage from each of the windings 36, 37 and 38 into two portions, combining each of the two portions with a reference voltage in a pair of rectifiers in such a manner that one rectified portion aids the rectified reference voltage and the other rectified portion opposes the rectified reference voltage so that the output voltage from one rectifier is the sum of one of the portions and the reference voltage, and the output voltage from the other rectifier is the difference between the other portion and the reference voltage. To this end the output coil 36 is connected by means of a lead 50 to a common lead 51 connecting one side of the input of a pair of rectifiers 52 and 53, and the output coil 37 is connected by means of a lead 54 to a common lead 55 connecting one side of the input of another pair of rectifiers 56 and 57, while the output coil 38 is likewise connected by means of a lead 58 to a common lead 59 connecting one side of the input of a third pair of rectifiers 60 and 61.

The other sides of the inputs of rectifiers 52, 56

and 61 are connected by a common lead 62 to one output terminal of the frequency doubler 35 which supplies the reference voltage, and the other sides of the inputs of rectifiers 53, 57 and 60 are connected by means of a common lead 63 to the other output terminal of the frequency doubler 35.

Since the output voltages from coils 36, 37 and 38 are second harmonics of the fundamental frequency of the exciting current flowing in the input coil 32 of the transmitter 29, the reference voltage must be of the same frequency as the output voltages. For this reason the frequency doubler is employed in order to double the frequency of the alternating current from the same source from which the exciting winding 32 is energized.

The resultant rectified voltages are now used to energize the respective pairs of stator windings 41-42, 43-44 and 45-46 of the receiver. Accordingly, the output of rectifier 52 of the pair of rectifiers is connected to stator coil 43 by means of leads 64, 65 while the output of rectifier 53 of the same pair of rectifiers is connected to stator coil 44 by means of leads 66, 67, said coils 43, 44 being in inductive relation with each other and, as previously pointed out, constitute one pair of the three pairs of stator coils angularly spaced 120 degrees apart around the magnet rotor 47 of the receiver.

Likewise, the outputs of the second pair of rectifiers 56, 57 are respectively connected to the second pair of stator coils 41, 42 by means of leads 68, 69 and 70, 71 and the outputs of the third pair of rectifiers 60, 61 are respectively connected to the third pair of stator coils 45, 46 by means of leads 72, 73 and 74, 75.

Now, by virtue of the arrangement of each of the pairs of rectifiers 52-53, 56-57 and 60-61, the one rectified portion of each of the output voltages from coils 36, 37, 38 opposes the rectified reference voltage as shown by the two arrows pointing in opposite directions in rectifiers 52, 56 and 61, while the other rectified portion of each of the output voltages from coils 36, 37, 38 aids the rectified voltage as shown by the arrows pointing in the same direction in rectifiers 53, 57 and 60.

Thus, the direct current in each of the stator coils 41, 43 and 45 of each cooperating pair of coils is the difference between the rectified voltage from each of the output coils 36, 37, 38 and the reference voltage, while the direct current in each of the stator coils 42, 44 and 46 of each cooperating pair is the sum of the rectified voltage from each of said output coils 36, 37, 38 and the reference voltage. The resultant uni-directional magnetic field produced at the receiver 30 by the direct currents flowing in the three pairs of coils 41-42, 43-44 and 45-46 will now have a direction such that when it reacts with the uni-directional field of the receiver magnet rotor 47, the latter will be caused to rotate to an angular position corresponding to the angular position of the transmitter magnet rotor 48, thereby actuating the pointer 49 to indicate said position. Thus, rotation of the transmitter rotor is transmitted to the receiver to cause corresponding rotation of the receiver rotor, and then the latter rotation may be used for indicating purposes as shown, or the receiver rotor 47 may be connected to actuate a control element of an automatic control system such as an aircraft automatic pilot, for example, when the transmitter is arranged to transmit a compass indi-

cation of the course on which the aircraft is to be maintained by the automatic pilot.

It is to be noted that neither the voltages from the output coils 36, 37 and 38 acting alone, nor the reference voltage from the frequency doubler acting alone, will produce a resultant field at the receiver, because in either case the fields of the coils of each pair of stator coils will be equal and in opposite directions, but when the voltages from the output coils 36, 37, 38 and the reference voltage act together, as described hereinbefore, the resultant field at the receiver will be in such a direction as to rotate the receiver rotor 47 to an angular position corresponding to the angular position of the transmitter rotor 48.

A third embodiment of the invention is shown in Fig. 3 wherein the transmitter is substantially the same as that shown in Fig. 2, except that the output coils 36, 37 and 38 are not Y-connected but each has two separate output terminals. Nevertheless, the output voltages from said output coils 36, 37 and 38 are second harmonics of the fundamental frequency of the alternating current flowing in the exciting input winding 32 and, therefore, the frequency doubler is again used in order to provide a reference voltage having the same frequency as the voltages from output coils 36, 37, 38. The receiver, shown at 16, is also of the direct current type but is different from the receivers shown in Figs. 1 and 2 and, as illustrated, comprises a stator having three windings 77, 78 and 79 connected at the junction 80 to form a Y-connected three-phase type of rotor, said windings being angularly spaced 120 degrees apart in the same manner as in the receivers of Figs. 1 and 2, and cooperate with a magnet rotor 81 drivably connected to a pointer 82 of an indicator 83.

As in Fig. 2, the second harmonic voltage of each of the output coils 36, 37, 38 is combined with a reference voltage of the same frequency, but by means of a special coupling transformer instead of in the rectifiers, and only three rectifiers are used instead of six. The special coupling transformer, as shown, has four windings 84, 85, 86 and 87 wound in inductive relation on a common core (not shown), the reference voltage being introduced in the winding 87 which is connected to the frequency doubler 35 by means of leads 88 and 89. This reference voltage is then induced into the windings 84, 85 and 86 in which the second harmonic voltages are also present by virtue of the fact that one end of each of the output coils 36, 37 and 38 is connected to one end of each of the windings 84, 85 and 86, respectively, by means of leads 90, 91 and 92, respectively. The other end of each of said output coils 36, 37 and 38 is connected to a corresponding input terminal of full-wave rectifiers 93, 94 and 95 respectively, by means of leads 96, 97 and 98, while the other input terminal of each of said rectifiers is connected to the other ends of said output coils 36, 37 and 38 by means of leads 99, 100 and 101, respectively.

Thus, it will be seen that the voltage rectified by each of the rectifiers 93, 94 and 95 is the algebraic sum of the reference voltage and the second harmonic voltage of the corresponding one of said output coils 36, 37 and 38. These rectified voltages are then supplied to the receiver stator windings 77, 78 and 79, respectively. To this end, the output terminals of rectifier 93 are connected to winding 77 by means of leads 102, 103, resistor 104 and a common lead 105 which is connected to the junction point 80 of all of said

receiver stator windings, while the output terminals of rectifier 94 are connected to the second stator winding 78 by means of leads 106, 107, resistor 108 and common lead 105. Likewise the output terminals of rectifier 95 are connected to the third stator winding 79 by means of lead 109, 110, resistor 111 and the common lead 105.

In addition to the energization of the receiver stator coils 77, 78, 79 by the rectified voltages from the rectifiers 93, 94, 95, a direct current voltage is supplied to said coils from supply lines 112, 113 through resistors 114, 115, 116 and leads 117, 118 and 119, respectively, said direct current voltage being adjusted to such a value in each of said stator windings as to be equal and opposite to the D. C. component of the rectified voltage from the corresponding rectifier which results from the rectification of the reference voltage from the frequency doubler 35. This is accomplished by disconnecting the transmitter output coils 36, 37, 38 from the coupling transformer windings 86, 84, 85 so that only the reference voltage is supplied to the rectifiers 93, 94, 95, and adjusting the D. C. voltage until there is no current flow in the receiver stator windings 77, 78, 79. Then the transmitter output coils 36, 37, 38 are re-connected again to the coupling transformer windings 86, 84, 85, thereby causing rectification of the second harmonic voltages from said output coils 36, 37, 38 together with the reference voltage from the frequency doubler 35 to produce a resultant D. C. voltage in each of the receiver stator windings 77, 78, 79 which is a function of the second harmonic voltage of the corresponding one of the output coils 36, 37, 38, respectively. These D. C. voltages then produce a resultant uni-directional field having such an angular direction that when it reacts with the field of the magnet rotor 81, the latter is rotated to an angular position corresponding to the angular position of the transmitter magnet rotor 46 to actuate the pointer 22 of indicator 83 which then indicates said position.

Novel means are thus provided for transmitting motion from one point to another and remote point, and particularly for transmitting angular motion for indicating and/or control purposes, whereby an alternating current type of transmitter may be readily used with a direct current type of receiver.

Although three embodiments of the invention have been specifically illustrated and described, various changes and modifications in the form, construction and relative arrangement of parts and circuits, which will now become apparent to those skilled in the art, may be made without departing from the scope of the invention. Reference is therefore to be had to the appended claims for a definition of the limits of the invention.

What is claimed is:

1. In combination, a transmitter of the alternating current type having an annular core of magnetically permeable material arranged to be traversed by a uni-directional magnetic field for inducing a magnetic flux therein, said core and uni-directional field being relatively angularly movable, an alternating current input winding wound on said core around its circumference, a plurality of equally angularly spaced alternating current output windings wound on said core in inductive relation with said input winding, an alternating current source connected to energize said input winding for periodically varying the magnetic flux in said core, whereby an alternating

voltage is induced in each of said output windings which is an even harmonic of the fundamental frequency of said energizing current and the magnitude of which is a function of the relative angular relation between said core and the uni-directional field, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means to produce a resultant uni-directional magnetic field having an angular direction corresponding to the direction of the uni-directional field at the transmitter with respect to the annular core thereof, and a rotor actuated by the resultant field of said receiver stator windings to an angular position corresponding to the angular direction of the uni-directional field at the transmitter.

2. In combination, a transmitter of the alternating current type having an annular core of magnetically permeable material arranged to be traversed by a uni-directional magnetic field for inducing a magnetic flux therein, said core and uni-directional field being relatively angularly movable, an alternating current input winding wound on said core around its circumference, a plurality of equally angularly spaced alternating current output windings wound on said core in inductive relation with said input winding, an alternating current source connected to energize said input winding for periodically varying the magnetic flux in said core, whereby an alternating voltage is induced in each of said output windings which is an even harmonic of the fundamental frequency of said energizing current and the magnitude of which is a function of the relative angular relation between said core and the uni-directional field, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means to produce a resultant uni-directional magnetic field having an angular direction corresponding to the direction of the uni-directional field at the transmitter with respect to the annular core thereof, a rotor actuated by the resultant field of said receiver stator windings to an angular position corresponding to the angular direction of the uni-directional field at the transmitter, and means actuated by said receiver rotor.

3. In combination, a transmitter of the alternating current type having an annular core of magnetically permeable material arranged to be traversed by a uni-directional magnetic field for inducing a magnetic flux therein, said core and uni-directional field being relatively angularly movable, an alternating current input winding wound on said core around its circumference, a plurality of equally angularly spaced alternating current output windings wound on said core in inductive relation with said input winding, an alternating current source connected to energize

size said input winding for periodically varying the magnetic flux in said core, whereby an alternating voltage is induced in each of said output windings which is an even harmonic of the fundamental frequency of said energizing current and the magnitude of which is a function of the relative angular relation between said core and the uni-directional field, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means to produce a resultant uni-directional magnetic field having an angular direction corresponding to the direction of the uni-directional field at the transmitter with respect to the annular core thereof, and a rotor providing a uni-directional magnetic field which reacts with the resultant field produced by said receiver stator windings to actuate said rotor to an angular position corresponding to the direction of the uni-directional field at the transmitter.

4. In combination, a transmitter of the alternating current type comprising a stator having an annular core of magnetically permeable material provided with an alternating current input winding around its circumference and a plurality of equally angularly spaced alternating current output windings in inductive relation with said input winding, a rotor comprising a rotatable magnet in magnetic relation with said core and windings for inducing a uni-directional flux in said core, a source of alternating current connected to said input winding for periodically varying the uni-directional flux in said core, whereby an alternating voltage is induced in each of said output windings which is an even harmonic of the frequency of said energizing current and the magnitude of which is a function of the angular position of said magnet rotor with respect to said core, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means to produce a resultant uni-directional magnetic field having an angular direction corresponding to the angular position of the transmitter magnet rotor, and a receiver rotor actuated by the resultant field of said receiver stator windings to an angular position corresponding to the angular position of said transmitter rotor.

5. In combination, a transmitter of the alternating current type comprising a stator having an annular core of magnetically permeable material provided with an alternating current input winding around its circumference and a plurality of equally angularly spaced alternating current output windings in inductive relation with said input winding, a rotor comprising a rotatable magnet in magnetic relation with said core and windings for inducing a uni-directional flux in said core, a source of alternating current con-

nected to said input winding for periodically varying the uni-directional flux in said core, whereby an alternating voltage is induced in each of said output windings which is an even harmonic of the frequency of said energizing current and the magnitude of which is a function of the angular position of said magnet rotor with respect to said core, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means to produce a resultant uni-directional magnetic field having an angular direction corresponding to the angular position of the transmitter magnet rotor, and a receiver rotor providing a uni-directional magnetic field which reacts with the resultant field of said receiver stator windings to actuate said receiver rotor to an angular position corresponding to the angular position of said transmitter rotor.

6. In combination, a transmitter of the alternating current type comprising a stator having an annular core of magnetically permeable material provided with an alternating current input winding around its circumference and a plurality of equally angularly spaced alternating current output windings in inductive relation with said input winding, a rotor comprising a rotatable magnet in magnetic relation with said core and windings for inducing a uni-directional flux in said core, a source of alternating current connected to said input winding for periodically varying the uni-directional flux in said core, whereby an alternating voltage is induced in each of said output windings which is an even harmonic of the frequency of said energizing current and the magnitude of which is a function of the angular position of said magnet rotor with respect to said core, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means to produce a resultant uni-directional magnetic field having an angular direction corresponding to the angular position of the transmitter magnet rotor, a receiver rotor actuated by the resultant field of said receiver stator windings to an angular position corresponding to the angular position of said transmitter rotor, and means actuated by said receiver rotor.

7. In combination, a transmitter of the alternating current type having an annular core of magnetically permeable material arranged to be traversed by a uni-directional magnetic field for inducing a magnetic flux therein, said core and uni-directional field being relatively angularly movable, an alternating current input winding wound on said core around its circumference, a plurality of equally angularly spaced alternating current output windings wound on said core in inductive relation with said input winding,

an alternating current source connected to energize said input winding for periodically varying the magnetic flux in said core, whereby an alternating voltage is induced in each of said output windings which is an even harmonic of the fundamental frequency of said energizing current and the magnitude of which is a function of the relative angular relation between said core and the uni-directional field, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means, a source of direct current connected to energize each of said direct current receiver windings for impressing on each of said windings a direct current voltage which is equal and opposite to the rectified reference voltage in each of said windings whereby only the rectified voltages from the output coils of the transmitter are effective to produce a resultant uni-directional magnetic field having an angular direction corresponding to the direction of the uni-directional field at the transmitter with respect to the annular core thereof, and a rotor actuated by the resultant field of said receiver stator windings to an angular position corresponding to the angular direction of the uni-directional field at the transmitter.

8. In combination, a transmitter of the alternating current type having an annular core of magnetically permeable material arranged to be traversed by a uni-directional magnetic field for inducing a magnetic flux therein, said core and uni-directional field being relatively angularly movable, an alternating current input winding wound on said core around its circumference, a plurality of equally angularly spaced alternating current output windings wound on said core in inductive relation with said input winding, an alternating current source connected to energize said input winding for periodically varying the magnetic flux in said core, whereby an alternating voltage is induced in each of said output windings which is an even harmonic of the fundamental frequency of said energizing current and the magnitude of which is a function of the relative angular relation between said core and the uni-directional field, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means, a source of direct current connected to energize each of said direct current receiver windings for impressing on each of said windings a direct current voltage which is equal and opposite to the rectified reference voltage in each of said windings whereby only the rectified voltages from the output coils of the transmitter are effective to produce a resultant uni-directional magnetic field having an angular direction corresponding to the direction of the uni-directional field at the transmitter.

transmitter with respect to the annular core thereof, a rotor actuated by the resultant field of said receiver stator windings to an angular position corresponding to the angular direction of the uni-directional field at the transmitter, and means actuated by said receiver rotor.

9. In combination, a transmitter of the alternating current type comprising a stator having an annular core of magnetically permeable material provided with an alternating current input winding around its circumference and a plurality of equally angularly spaced alternating current output windings in inductive relation with said input winding, a rotor comprising a rotatable magnet in magnetic relation with said core and windings for inducing a uni-directional flux in said core, a source of alternating current connected to said input winding for periodically varying the uni-directional flux in said core, whereby an alternating voltage is induced in each of said output windings which is an even harmonic of the frequency of said energizing current and the magnitude of which is a function of the angular position of said magnet rotor with respect to said core, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means for energization by said rectified voltages, and a source of direct current for additionally energizing said direct current receiver stator windings for impressing on each of said windings a direct current voltage which is equal and opposite to the rectified reference voltage component in each of said windings, whereby only the rectified voltages from the output windings of said transmitter are effective to produce a resultant uni-directional magnetic field having an angular direction corresponding to the angular position of the transmitter rotor, and a receiver rotor actuated by the resultant field of said receiver stator windings to an angular position corresponding to the angular position of said transmitter rotor.

10. In combination, a transmitter of the alternating current type comprising a stator having an annular core of magnetically permeable material provided with an alternating current input winding around its circumference and a plurality of equally angularly spaced alternating current output windings in inductive relation with said input winding, a rotor comprising a rotatable magnet in magnetic relation with said core and windings for inducing a uni-directional flux in said core, a source of alternating current connected to said input winding for periodically varying the uni-directional flux in said core, whereby an alternating voltage is induced in each of said output windings which is an even harmonic of the frequency of said energizing current and the magnitude of which is a function of the angular position of said magnet rotor with respect to said core, means for combining with each of the voltages from said output windings a reference alternating voltage having the same frequency as said output voltages, a plurality of rectifying means for rectifying the combined reference voltage and output voltage from each of said output windings separately, and a direct current type of receiver comprising a stator having a plurality of equally angularly spaced direct current windings respectively connected to the outputs of said plurality of rectifying means for energization by said rectified voltages, and a source of direct current for additionally energizing said direct current receiver stator windings for impressing on each of said windings a direct current voltage which is equal and opposite to the rectified reference voltage component in each of said windings, whereby only the rectified voltages from the output windings of said transmitter are effective to produce a resultant uni-directional magnetic field having an angular direction corresponding to the angular position of the transmitter rotor, and a receiver rotor actuated by the resultant field of said receiver stator windings to an angular position corresponding to the angular position of said transmitter rotor.

rent type of receiver comprising a stator having a plurality of equally angularly spaced direct current windings respectively connected to the outputs of said plurality of rectifying means for energization by said rectified voltages, and a source of direct current for additionally energizing said direct current receiver stator windings for impressing on each of said windings a direct current voltage which is equal and opposite to the rectified reference voltage component in each of said windings, whereby only the rectified voltages from the output windings of said transmitter are effective to produce a resultant uni-directional magnetic field having an angular direction corresponding to the angular position of the transmitter rotor, and a receiver rotor providing a uni-directional magnetic field which reacts with the resultant field of said receiver stator windings to actuate said receiver rotor to an angular position corresponding to the angular position of said transmitter rotor.

11. In combination, a transmitter of the alternating current type comprising a stator having an annular core of magnetically permeable material provided with an alternating current input winding around its circumference and a plurality of equally angularly spaced alternating current output windings in inductive relation with said input winding, a rotor comprising a rotatable magnet in magnetic relation with said core and windings for inducing a uni-directional flux in said core, a source of alternating current connected to said input winding for periodically varying the uni-directional flux in said core, whereby an alternating voltage is induced in each of said output windings which is an even harmonic of the frequency of said energizing current and the magnitude of which is a function of the angular position of said magnet rotor with respect to said core, a plurality of pairs of rectifiers, the number of pairs of rectifiers corresponding to the number of output windings, means for combining in each pair of rectifiers each of the voltages from said output windings with a reference alternating voltage having the same frequency as said output voltages, whereby the rectified output voltage from one of each pair of said rectifiers is the sum of the rectified reference voltage and the rectified output voltage, and the rectified output voltage of the other of each pair of rectifiers is the difference between the rectified reference voltage and the rectified output voltage, and a direct current type of receiver having a plurality of pairs of direct current stator windings, the number of pairs of said windings corresponding to the number of pairs of rectifiers, and said pairs of windings being equally angularly spaced, means connecting one of each pair of said stator windings to the output of a corresponding one of said pairs of rectifiers, means connecting the other of each of said pairs of windings to the output of the corresponding other one of said pairs of rectifiers, whereby said pairs of stator windings produce a resultant uni-directional magnetic field having an angular direction corresponding to the angular position of a transmitter rotor, and a receiver rotor actuated by the resultant field of said receiver stator windings to an angular position corresponding to the angular position of said transmitter rotor.

12. In combination, a transmitter of the alternating current type comprising a stator having an annular core of magnetically permeable material provided with an alternating current input winding around its circumference and a plu-

rality of equally angularly spaced alternating current output windings in inductive relation with said input winding, a rotor comprising a rotatable magnet in magnetic relation with said core and windings for inducing a uni-directional flux in said core, a source of alternating current connected to said input winding for periodically varying the uni-directional flux in said core, whereby an alternating voltage is induced in each of said output windings which is an even harmonic of the frequency of said energizing current and the magnitude of which is a function of the angular position of said magnet rotor with respect to said core, a plurality of pairs of rectifiers, the number of pairs of rectifiers corresponding to the number of output windings, means for combining in each pair of rectifiers each of the voltages from said output windings with a reference alternating voltage having the same frequency as said output voltages, whereby the rectified output voltage from one of each pair of said rectifiers is the sum of the rectified reference voltage and the rectified output voltage, and the rectified output voltage of the other of each pair of rectifiers is the difference between the rectified reference voltage and the rectified output voltage, and a direct current type of receiver having a plurality of pairs of direct current stator windings, the number of pairs of said windings corresponding to the number of pairs of rectifiers, and said pairs of windings being equally angularly spaced, means connecting one of each pair of said stator windings to the output of a corresponding one of said pairs of rectifiers, means connecting the other of each of said pairs of windings to the output of the corresponding other one of said pairs of rectifiers, whereby said pairs of stator windings produce a resultant uni-directional magnetic field having an angular direction corresponding to the angular position of a transmitter rotor, a receiver rotor actuated by the resultant field of said receiver stator windings to an angular position corresponding to the angular position of said transmitter rotor, and means actuated by said receiver rotor.

13. In combination, a transmitter of the alternating current type having core means of magnetically permeable material arranged to be traversed by a uni-directional magnetic field for inducing a magnetic flux therein, said core means and uni-directional magnetic field being relatively angularly movable, coil means wound on said core means and having single circuit input connections and a plurality of equally angularly spaced output connections about said core means, a source of periodically varying current connected to energize the input of said coil means for periodically varying the magnetic flux in said core means, whereby an alternating voltage is induced in each of the outputs of said coil means, having a magnitude which is a function of the relative angular relation between said core means and the uni-directional magnetic field, means for combining with each of said output voltages a periodically varying reference voltage having the same frequency of variation as said output voltages, a plurality of rectifying means for rectifying the combined reference voltage and output voltage from each of said outputs separately, and a direct current type of receiver comprising a stator having a plurality of equally angularly spaced direct current windings respectively connected to the outputs of said plurality of rectifying means to produce a resultant uni-directional magnetic field having an angular direction corresponding

15

to the direction of the uni-directional magnetic field at the transmitter with respect to the core means thereof, and a receiver rotor actuated by the resultant magnetic field of said receiver stator windings to an angular position corresponding to the direction of the uni-directional field at the transmitter.

JOEL D. PETERSON.
